UNITED STATES PATENT OFFICE.

ANDREW J. CARMICHAEL AND ALBERT M. WUNDERLICH, OF NEW HAVEN, CONNECTICUT, ASSIGNORS TO THE GREIST MANUFACTURING COMPANY, A CORPORATION OF CONNECTICUT.

SEWING-MACHINE BRAIDER OR CORDER.

Application filed October 13, 1927. Serial No. 225,916.

This invention relates to a sewing machine braider or corder attachment and has for its object to provide an efficient device of this sort which may be conveniently secured to 5 or removed from the presser foot of a sewing machine. To this end the improved braider or corder comprises a transverse clamp by which the attachment may be secured to the presser foot of the machine, said clamp having a depending portion bent at a right angle 10 so as to extend horizontally for the proper attachment of a braid guide support which has an inclined forward portion on which the braid guide is slidably mounted, all as 15 will hereinafter more fully appear.

In the accompanying drawing Fig. 1 is a side view showing the braider attachment in operative relation to the presser foot and needle of a sewing machine. Fig. 2 is a plan view of the attachment and the sewing machine presser foot. Figs. 3 and 4 are opposite side views of the attachment. Fig. 5 is a detail view of the clamp and clamp frame, and Fig. 6 a detail plan view of the braid 25 guide.

Referring to the drawing, 12 denotes the presser bar of a sewing machine and 13 denotes a presser foot attached to the presser bar by a nut 14 between which and a shoulder at the lower end of the presser bar the presser foot is clamped in a well known manner, said presser bar having at its lower end a threaded tenon 15 for the reception of the said nut 14. The presser foot is provided with a slotted or forked forward end 13^a, the slot in said foot terminating at its rear end in a needle hole 13^b. Also the said presser foot is preferably provided on its upper side, just forward of the needle hole, with a small transverse rib 13^c.

The braiding or cording attachment comprises a clamp member 16 integral with which is a depending portion 16^a which is bent at its lower end at a right angle to form a forwardly extending horizontal part 16^b to which is attached, by rivets 17, the horizontal portion of a braid guide support 18 having an inclined upwardly extending forward part. The said clamp member comprises upper and lower jaws which may be closed together by a thumb screw 19 the lower end of which is tapped in the lower jaw of the clamp. It will be apparent that by means of said thumb screw the jaws of the clamp may

be closed together in order to secure the clamp 55 to the upper horizontal part of the presser foot 13.

Mounted on the upwardly inclined forward part of the braid guide support is a braid guide consisting of a thin plate 20 having laterally extending fingers 21 and 22, the finger 21 being provided with an opening 23 through which a braid or cord, as x, may be passed downwardly and then over the finger 22 as indicated in Fig. 1. The braid guide 20 is slidably mounted, by means of shouldered rivets 24, on the inclined forward part of the braid guide support 18, so that it may be raised or lowered; and for convenience in effecting this raising and lowering adjustment the said braid guide is provided at its top or forward end with a small handle 25. When the braid guide is in working position, as indicated in Figs. 1, 2 and 3, the finger 22 will be brought adjacent to or in contact with a transverse rib 13^c on the presser foot, and in this position the said finger 22 will practically close the slot in the forward portion of the presser foot so that the braid will be guided up close to the needle-hole 13^b in the 80 presser foot in such a manner that the braid will be held close to the needle 26, thus permitting the work to be turned at sharp angles in doing braiding or cording requiring sharp turns, as in making square or angular braided 85 figures on the work.

The object of slidably mounting the braid guide on its support is for convenience in mounting the attachment on the presser foot or in removing it therefrom. In attaching 90 the braider to the presser foot it is necessary to tilt the clamp portion over slightly in an upward direction, and if the finger 22 were at such time down close to the work this could not be conveniently done, but by sliding the 95 braid or guide upward on its support, and thus removing the finger 22 somewhat from the work, sufficient space between said finger and the work is afforded to permit of this tilting or tipping movement of the attachment 100 in mounting it in place on the presser foot, or in removing it therefrom. While in the working position of the braid guide it is desirable that said finger 22 should occupy a position close to the work. The drag of the braid 105 through the finger 21 and over the finger 22, when the braid guide is in working position, will tend to hold the said finger 22 down close

to the work, so that the braid guide may be mounted on a support in such a manner as to be moved upward and downward easily by means of the handle 25, when the finger 22 is to be lifted from the work, or returned to working position.

In order to properly position the clamp on the presser foot the upper and lower members thereof are provided with shoulders 27 so as to position the braider laterally on the presser foot, the proper longitudinal or back and forth position of the braider being determined by setting the clamp against the presser-bar 12, as denoted in Fig. 2.

Having thus described our invention we claim and desire to secure by Letters Patent:

1. A sewing machine braider comprising a braid guide support having an upwardly extending inclined forward part, a braid guide 20 slidingly mounted on said inclined forward part and having two laterally extending fingers one above the other, the upper one of said fingers being provided with a braid opening, and means for attaching the said braid guide support to the presser foot of a sewing machine.

2. A sewing machine braider comprising a braid guide support having an upwardly extending inclined forward part, a braid guide 30 slidingly mounted on said inclined forward part and having two laterally extending fingers one above the other, the upper one of said fingers being provided with a braid opening, and means for attaching the said braid guide support to the presser-foot of a sewing machine, said attaching means comprising a clamp member having a depending portion bent at its lower end to form a horizontally extending part to which the said braid guide support is attached.

3. A sewing machine braider comprising a braid guide support having an upwardly extending inclined forward part, a braid guide 45 slidingly mounted on said inclined forward part and having two laterally extending fingers one above the other, the upper one of said fingers being provided with a braid opening, and means for attaching the said braid guide support to the presser-foot of

a sewing machine, said attaching means comprising a clamp member having a depending portion bent at its lower end to form a horizontally extending part to which the said braid guide support is attached, the jaws of said clamp member having shoulders for positioning said member laterally on a sewing machine presser foot.

4. A sewing machine braider comprising a braid guide support having an upwardly extending inclined forward part, a braid 60 guide slidingly mounted on said inclined forward part and having two laterally extending fingers one above the other, the upper one of said fingers being provided with a braid opening, and means for attaching the 65 said braid guide support to the presser foot of a sewing machine, combined with a presser foot having, at its toe portion, an open slot terminating at its rear end in a needle-opening, said slot being practically closed in front 70 of said needle-opening by the lower finger of said braid guide when said guide is in its lowered or working position.

5. A sewing machine braider comprising a braid guide support having an upwardly extending inclined forward part, a braid guide 75 slidingly mounted on said inclined forward part and having two laterally extending fingers one above the other, the upper one of said fingers being provided with a braid 80 opening, and means for attaching the said braid guide support to the presser foot of a sewing machine, combined with a presser-foot having, at its toe portion, an open slot terminating at its rear end in a needle-opening, said slot being practically closed in front 85 of said needle-opening by the lower finger of said braid guide when said guide is in its lowered or working position, said presser foot having also, on its upper face, a trans- 90 verse rib in front of said needle-opening at a point registering with said lower finger when said finger is depressed to working position.

In testimony whereof we affix our signatures.

ANDREW J. CARMICHAEL.
ALBERT M. WUNDERLICH.
